SPORTS NET SUPPORT

David L. Malcolm, Jr., Glen Rock, N. J., assignor
to The Linen Thread Co., Inc., Paterson, N. J.,
a corporation of Delaware

Application September 13, 1949, Serial No. 115,413

5 Claims. (Cl. 273—29)

1

The present invention relates to sports nets, and has special reference to tennis nets.

Conventional nets of this character are commonly suspended by means of a cable threaded through the top binding of the net with its ends secured to posts, and ropes extending from the ends of the top and bottom bindings and tied to the posts. Heretofore, considerable difficulty has been experienced owing to the tendency of the central longitudinal cords of the net webbing to shrink and the ends of the net to bow inwardly or otherwise become objectionably distorted.

The principal object of the present invention is to provide means, which is simple and strong in construction and convenient in use, for holding the ends of the net in proper position parallel with the supporting posts, thus effectively overcoming the difficulty referred to.

The invention is illustrated, by way of example, in the accompanying drawings, in which:

Figure 1 is a side view of a tennis net embodying features of the invention in their preferred form, the central portion of the net being broken away to save space;

Fig. 2 is a detail side view, on an enlarged scale and with parts broken away, of one end portion of the net;

Figs. 3 and 4 are sectional views on an enlarged scale respectively taken on the lines 3—3 and 4—4 of Fig. 2; and

Figs. 5, 6 and 7 are views respectively corresponding to Figs. 1, 2 and 3 of a modified form.

The present application is a continuation in part of my pending application Serial No. 729,932, filed February 21, 1947 (now abandoned).

The net illustrated in the drawings is provided with the usual webbing 2, top binding 4, end tapes or bindings 6, and bottom tape or binding 8, the bindings being made of duck or other suitable material. The net may be suspended from and secured to the usual posts 10 by means of a cable 12 which extends through the top binding 4, tie ropes 14 which are laced through grommets 16 in the ends of the top binding 4, and tie ropes 17 which extend through loops 18 at the ends of the binding 8. The parts above referred to may be and preferably are of conventional form.

In accordance with the present invention, in the form shown in Figs. 1, 2, 3 and 4, a strip of duck or other strong fabric is folded over the outer edge portion of each end binding 6 and secured thereto by stitching 20 so as to form a sleeve 22. The upper end of this sleeve 22 is open, and its lower end is preferably closed by turning its lower edges 24 upwardly and sewing them together and

2

to the binding 6 by means of a line of stitching 26.

Inserted in each sleeve 22 is a stiffening member 28 which may be made of iron, aluminum or other suitable material, the sleeve closely embracing said member. This stiffening member is preferably V-shape in cross-section, the outer margin of the binding 6 extending into the V. The lower end of the member 28 may rest on the bottom of the sleeve 22. The upper end portion of said member is inclined upwardly and inwardly, and is bifurcated with its arms 30 arranged at opposite sides of the top binding 4. The ends of the arms 30 are provided with apertures 32 which register with the outer grommet 16. In lacing the tie ropes 14 through the grommets, they are also inserted through the apertures in the ends of the arms 30. Thus the inclined arms are firmly secured to opposite sides of the associated end of the top binding at points spaced inwardly from the upper end of the sleeve and in proximity to the suspension cable whereby the normally flexible ends of the net are securely held in position throughout their length.

With this construction, upon securing the net to the posts 10 in the customary manner as above described, the stiffening members 28, closely embraced by the flexible sleeves 22 and firmly secured at their upper ends as above described, insure the ends of the net being held in proper position parallel with the posts. Thus shrinking of the cords of the net webbing and inward bowing or other objectionable distortion of the ends of the net are effectively prevented. It will be apparent that the stiffening members do not affect the flexibility of the body of the net or interfere in attaching the net to the supporting posts or removing it therefrom. Also that they may be easily inserted in the sleeves and attached to the top binder, and may be easily removed when desired to repair the net or for other purposes.

In the form shown in Figs. 5, 6 and 7 instead of the bracing or stiffening members 28, members 34 are employed. These members may consist of rods or dowels 36 which may be of wood and have their lower ends rounded over, and their upper ends reduced in diameter to receive embracing sheet metal tubes or ferrules 38. The portions of the ferrules 38 extending about the upper ends of the dowels 36 have their outer peripheries of the same diameter as the diameter of the body of the dowels, and the ferrules are firmly secured to the dowels in any suitable manner as by forming indentations 40 therein which are forced into the material of the dowels. The portions of the fer-

rules 38 above the dowels 36 are flattened, and each is provided with an aperture 42.

Each of these stiffening members 34 is removably inserted in a sleeve 44 which may be formed by folding a strip of duck or other suitable fabric over the end tape or binding of the net, and securing the longitudinal margins of the strip to the binding by sewing or other means. Preferably each sleeve 44 extends to the lower end of the end binding. The sleeves 44 serve to reinforce the end bindings, but if desired may be made integral therewith.

The upper flattened end of each stiffening member is inserted between the sides of the end extension of the top binding 4. The sides of the projecting end of the top binding may have eyelets or grommets 46 secured therein in alinement with each other and with the aperture 42 in the end of the member 38. A grommet 48 is provided near the lower end of each sleeve 44, this grommet extending through the secured portions of the sides of the sleeve and the adjacent end binding.

The cords 14 for securing the net to the posts 10 may each be threaded through the registering grommets 46 and aperture 42, and through the usual grommet 16. The cords 17 for securing the lower corners of the net to the posts 10 may each be looped through the grommet 48, and then the remaining portion thereof passed through the loop so that when the cord is tightened the lower portion of the sleeve 44 and the dowel 36 is firmly held.

It will be apparent that in this form also the stiffening members 34 may be easily removed and replaced, and that upon securing the net to the posts 10 as above described, the bracing or stiffening members 34 extending through the pockets or sleeves 44 and firmly secured at their upper ends to the top binding and at their lower ends to the adjacent ends of the end and bottom bindings, insure the ends of the net being held in proper position with relation to the posts 10. Thus this construction prevents shrinkage, makes the mesh hang secure and true, eliminates gaps at the posts, and prolongs net life by spreading the tension evenly. The stiffening members 34 made up of the wooden dowels 36 are of light construction, and the ferrules 38 at the upper ends of the posts provide a strong construction for reinforcing the dowels and securing them to the net. While it is preferred to employ the ferrules 38 in order to obtain maximum strength, it will be apparent that in certain instances the stiffening members may be made entirely of wood.

As will be evident to those skilled in the art, my invention permits various modifications without departing from the spirit thereof or the scope of the appended claims.

What I claim is:

1. The combination with a sports net of the class described having top, bottom and end bindings, grommets adjacent the ends of the top binding, and tie ropes laced through the grommets for securing the net to supporting posts, of a flexible strip folded over the outer margin of at least one of the end bindings with its edges secured thereto so as to form a sleeve, the upper end of the sleeve being open and its lower end being closed, a stiffening member of V-form in cross-section inserted in the sleeve and arranged at opposite sides of said margin of the associated binding with its lower end adjacent the bottom of the sleeve, said member having its upper end bifurcated so as to straddle said top binding and in-

clined upwardly and inwardly, and the arms of said bifurcated end having apertures registering with one of the grommets in the binding, said tie ropes extending through said apertures to secure the stiffening member to the top binding.

2. In a sports net of the class described having top, bottom and end bindings, grommets adjacent the ends of the top binding, tie ropes laced through the grommets for securing the top binding to supporting posts, and tie ropes for securing the ends of the bottom binding to the supporting posts, the improvement which comprises sleeves secured to said end bindings with their ends extending in proximity to said top and bottom bindings, and a stiffening member removably inserted in each of said sleeves and having its upper end bifurcated so as to straddle said top binding, the arms of the bifurcated end of each stiffening member having apertures adapted to register with one of the grommets in said top binding to enable the tie rope laced through said grommets to be also laced through said apertures to secure the stiffening member to the top binding.

3. A sports net of the class described having top, bottom and end bindings, grommets adjacent the ends of the top binding, and tie ropes laced through the grommets for securing the net to supporting posts, in combination with sleeves secured to the ends of the net with their ends extending in proximity to said top and bottom bindings, and a stiffening member removably inserted in each of said sleeves, the upper end of each stiffening member having an aperture adapted to register with one of the grommets in said top binding to enable the tie rope laced through said grommets to be also laced through said aperture to secure the stiffening member to the top binding.

4. In a sports net of the class described, the combination of top, bottom and end bindings, said top binding being folded over the upper longitudinal margin of the net and having its ends projecting beyond the end bindings, each of said projecting ends having the sides thereof provided with registering grommets, said top binding also having grommets spaced inwardly from the end bindings, tie ropes adapted to be laced through the last-mentioned grommets and said registering grommets to secure the top binding to supporting posts, tie ropes for securing the lower corners of the net to the supporting posts, sleeves secured to the ends of the net with their ends extending in proximity to said top and bottom bindings, and a stiffening member removably inserted in each of said sleeves with its upper end extending between the sides of the projecting end of the top binding, said upper end of the stiffening member having an aperture in alinement with said registering grommets so as to enable the tie rope laced through said registering grommets to be also laced through said aperture in the stiffening member to secure the stiffening member to the top binding.

5. A stiffening member for one end of a sports net of the class described having top, bottom, and end bindings, grommets adjacent the ends of the top binding, and tie ropes laced through the grommets for securing the ends of the top binding to supporting posts, comprising a dowel having a ferrule on its upper end with the upper end of the ferrule flattened and projecting beyond the dowel and provided with an aperture, the stiffening member being adapted to be inserted in a sleeve secured to one of the end bindings with said

2,518,702

5

aperture in the ferrule registering with one of the grommets in the top binding to enable the tie rope laced through said grommets to be also laced through the aperture in said ferrule.
